UNITED STATES PATENT OFFICE.

EDWARD A. CLUNGEON, OF PHILADELPHIA, PENNSYLVANIA, ASSIGNOR TO GEORGE A. REACH, OF PHILADELPHIA, PENNSYLVANIA.

DESIGN FOR A SIGN-BOARD.

No. 40,144.

Specification for Design.

Patented July 13, 1909.

Application filed May 22, 1909. Serial No. 497,811. Term of patent 7 years.

To all whom it may concern:

Be it known that I, EDWARD A. CLUNGEON, a citizen of the United States, residing at Philadelphia, in the county of Philadelphia and State of Pennsylvania, have invented a new, original, and ornamental Design for Sign-Boards, of which the following is a specification, reference being had to the accompanying drawing, forming part thereof.

The figure is a front elevation of the sign board, showing my new design.

I claim:

The ornamental design for a sign board, as shown.

EDWARD A. CLUNGEON.
